GUIDE ASSEMBLY FOR ARTICLE COATING MACHINES

Arie M. Mason, Prairie Village, Kans., assignor to Mason Plastics Co., Inc., Kansas City, Kans., a corporation of Kansas

Application June 1, 1954, Serial No. 433,483

10 Claims. (Cl. 118—405)

This invention relates to structure for use in machines for coating articles with suitable substances such as plastic materials and has for its primary object the provision of an improved guiding assembly adapted to receive articles of irregular diameters and maintain the same substantially centered along a rectilinear path of travel so that a more even and uniform coating of the substance is applied thereto.

It is the most important object of the instant invention to provide a guiding structure adapted for immersion in the substance to be used to coat an article and having a novel collet arrangement operable automatically to always remain in engagement with the article as it is advanced through the collet and thereupon through the coating substance, all to the end that the article is held centered, particularly with respect to a doctor plate used to wipe excess substance in the article.

An important object of the instant invention is to provide guide structure for use with coating machines of the kind contemplating advancement of the article through the substance so that an excess amount of the latter is always made available to the article, the guide including a resilient collet so arranged as to engage and hold the article against lateral movement at all times while it is being advanced through the substance.

It is an important aim of the instant invention to provide in a guide structure of the aforementioned character, a reciprocable segmented, resilient collet having a bore therethrough for receiving the article to be coated and including cam means for biasing the segments against the article at all times while it is rotated and advanced through the collet.

Other important aims and objects include the way in which a liner is provided to guide the article to the collet; the way in which the guide is utilized for releasing the parts which hold the collet in place; the manner of providing a spring bias on the collet to render the cam means effective in varying the diameter of the bore through the collet; the way in which an interlocking connection is provided to releasably hold the collet in place; the manner of feeding the coating substance to the article as it emerges from the outlet end of the collet and immediately prior to treatment by the said doctor plate; and the way in which all of the aforementioned structure is operably held in place within the substance by a specially formed guide body.

In the drawings:

Figure 1 is a side elevational view of a guide assembly for article coating machines showing the same operably mounted within a vat or container for the coating substance, parts being broken away and in section to reveal details of construction.

Fig. 2 is an enlarged, side elevational view of the guide assembly entirely removed from the vat shown in Fig. 1.

Fig. 3 is a longitudinal, cross-sectional view taken on line III—III of Fig. 2.

2

Fig. 4 is a transverse, cross-sectional view taken on line IV—IV of Fig. 3.

Fig. 5 is a transverse, cross-sectional view taken on line V—V of Fig. 3.

Fig. 6 is a longitudinal, cross-sectional view taken on line VI—VI of Fig. 5; and

Fig. 7 is an exploded, perspective view of the collet and the pressure ring forming a part of the guide assembly showing the same entirely removed from the guide body 10 of the assembly.

The field of coating articles of merchandise has increasingly expanded since the development of many new synthetic plastic materials because it has been found that such materials are capable of rendering various articles more resistant to wear, less subject to corrosion and other deterioration, stronger and more attractive.

In many applications advantageous results are experienced because of insulating properties of the coating substances. While the end results are extremely beneficial, it is most difficult to obtain an even, uniform coating of the plastic substances on the articles and such is necessary, not only from the standpoint of attractiveness, but utility. Voids, irregular surfaces and overlapping should be avoided as much as possible if the above-mentioned results and advantages are to be attained.

Such plastic substances commence drying immediately upon exposure to the atmosphere and unless the coating is substantially uniform throughout, the surface of the article being coated, the drying and setting, will likewise be nonuniform resulting in many "rejects" thereby increasing the cost of the entire operation.

According to the principles of the instant invention, the article to be coated is advanced through the coating substance and, by virtue of such complete immersion of the article therewithin at least momentarily, an excess of the substance is directed to the article so that there is always an assurance of a sufficient amount thereof on the article prior to its being "doctored" by removal of excess substance.

Thus, as shown in Fig. 1 of the drawings, there is provided a container or vat broadly designated by the numeral 10 adapted to receive the coating substance, and when the same is in the nature of a synthetic plastic, it is preferred that the same be in a highly viscous, gelatinous state, yet sufficiently fluid to flow freely to the article through a plurality of passages 12 formed in an elongated, tubular guide body broadly designated by the numeral 14.

Body 14 is carried by the container 10 partially immersed within the substance contained thereby and as shown in Fig. 1, body 14 extends through one wall 16 of the container 10 with shoulder 18 of body 14 engaging the inner face of wall 16. One end of the body 14 engages the opposite wall 20 of the container 10 and may be held in place by a circumscribing retainer ring 22 that may in turn be held in place with an outermost perforated ring 24 fastened to the wall 20.

A removable collet broadly designated by the numeral 26, mounted in the body 14 is made of any suitable resilient material and provided with an integral, out-turned, annular flange 28 on one end thereof, together with a frusto-conical head 30 integral with the opposite end of the tubular collet 26.

By virtue of the tubular nature of the collet 26 it is adapted to receive and guide an article 32 (Fig. 1) such as an elongated tube, rod, pole or the like, to be coated with the substance in container 10. The longitudinal bore through the collet 26 may be provided with an outlet end 34 of reduced diameter if desired, whereby to define the area of frictional engagement between the collet 26 and the article 32.

Collet 26 is provided with a plurality of longitudinal

slits 36 that extend through the head 30 but not through the flange 28, presenting a number of elongated fingers or segments 38, adapted to flex radially by virtue of the resilient nature of the material from which collet 26 is made. Head 30 is provided with an annular inclined cam surface 40 and flange 28 has a number of short pins 42 extending radially outwardly from its periphery.

An annular cam ring 44 held in place within body 14 by pins or the like 46, surrounds the head 30 of collet 26 in engagement with the cam surface 40 which it complementally fits. Cam ring 44 is provided with a seat 48 for one end of a spring 50 coiled about the collet 26 within the body 14.

A pressure ring 52 freely movable within the body 14 has a seat 54 for the opposite end of the spring 50 and is disposed in surrounding relationship to the flange 28 of collet 26. Pressure ring 52 is provided with a slot 56 for each pin 42 respectively, and a depression 58 on one face thereof registering with each slot 56 respectively. The said one face of pressure ring 52 opposite to spring seat 54, is also provided with a radial V-shaped groove 60 for each pin 42 respectively.

It is now seen that when the pins 42 are within the grooves 60 as shown best in Fig. 5 of the drawings, pressure ring 52 is disposed between the pins 42 and the spring 50, whereas the latter is interposed between the pressure ring 52 and the cam ring 44.

As the article 32 is advanced and rotated in the direction of the arrows shown in Fig. 1, it is guided into the collet 26 by a liner 62 fitted within the body 14 and provided with an article-receiving bore 64.

Liner 62 has an outturned flange 66 exteriorly of the body 14 and of the container 10 receiving a plurality of bolts 68 threaded into the proximal end of the body 14 for shifting the liner 62 longitudinally of the body 14 toward the pressure ring 52. Bolts 68 are freely rotatable in the flange 66, whereas a number of bolts 70 are threaded into the flange 66 as shown in Fig. 1, and abut the proximal end of the body 14 to lock the liner 62 in place in cooperation with the bolts 68 and to facilitate removal of the liner 62 after removal of the bolts 68.

The liner 62 is provided with a cavity 72 at its innermost end having a diameter sufficiently great to receive the flange 28 and its pins 42.

Assuming the various parts of the guide assembly to be assembled in the manner shown by Figs. 1 to 6 inclusive, the operation is as follows:

Through use of any suitable mechanism not herein shown, the article 32 is advanced rectilinearly and simultaneously rotated through the bore 64 of liner 62, thence through the collet 26, through the coating substance as the article 32 emerges from the outlet end 34 of collet 26, then through a circular opening 74 of a doctor plate 76 and finally through an opening 78 in the outside ring 24. It is noted that the doctor plate 76 is carried by the body 14 within a cavity 80 and held in place against the inner face of wall 29 by the ring 24.

By virtue of the resiliency of the material from which the collet 26 is made, the segments 38 thereof will spring outwardly in response to areas of increased diameter in the article 32 as such areas slide along the outlet end 34 of the collet 26. In this respect it is to be pointed out that notwithstanding the fact that the article 32 is of a general uniform diameter, in many instances the diameter of the article 32 varies, and by virtue of the continuous bias of the segments 38 on the article 32 as it is advanced and rotated, collet 26 will always hold the article 32 substantially centered with respect to the opening 74 in the doctor plate 76.

In addition to the inherent resiliency of the collet 26, spring 50 maintains a constant yieldable bias thereon tending to shift the collet 26 toward the liner 62 whereby the diameter of the bore through the collet 26 varies,

depending upon the position of the head 30 within the cam ring 44.

The coating substance enters the body 14 through the passages 12 and is directed to the article 32 in excess between the outlet end of the collet 26 and the doctor plate 76 by virtue of the frusto-conical configuration of head 30. Excess coating substance is immediately removed from the article 32 by the opening 74 in doctor plate 76 and, as the article 32 emerges from the opening 78 in ring 24, the even uniform coating of the substance on the article 32 commences drying immediately as it is subjected to the atmosphere.

It is extremely important to note that the entire guide assembly has been designed to accommodate articles 32 of differing diameters and to this end, the liner 62, the collet 26 and the doctor plate 76 are all quickly and readily interchangeable with like elements of differing sizes.

In making the change, removal of the ring 24 releases the doctor plate 76. The bolts 70 are thereupon retracted and the bolts 68 are used to force the liner 62 inwardly to a point where it engages the pressure ring 52 and shifts the latter toward the cam ring 44, thereby compressing the spring 50. This releases the pins 42 with respect to the grooves 60, whereupon by grasping the head 30, collet 26 may be turned 60° to align the pins 42 with the slots 56. The depressions 58 tend to guide the pins 42 into the slots 56, whereupon the collet 26 may be removed in its entirety from within the body 14.

After removal of the bolts 68, bolts 70 may be used to retract the liner 62 to a point where it can be slipped out of the body 14 and it is to be noted that all of these operations may be performed without removal of the body 14 from the container 10.

In replacing elements 62, 26 and 76 of differing sizes so far as internal diameters thereof are concerned, the steps just above outlined are simply reversed.

Having thus described the invention what is claimed as new and desired to be secured by Letters Patent is:

1. In structure for guiding articles through a coating substance, a collet having an article-receiving bore and a plurality of relatively movable sections; means including a cam ring surrounding the collet and engaging the sections for forcing the sections toward the article as it is advanced through the bore and upon shifting the collet in one direction; a pressure ring engaging the collet; resilient means interposed between the rings for yieldably holding the collet biased in said one direction; means interlocking the collet and the pressure ring for holding the collet against movement in the opposite direction; and means engageable with said pressure ring for shifting the latter against the force of said resilient means to a position permitting unlocking of the collet from the pressure ring.

2. In structure as set forth in claim 1 wherein said last-mentioned means is provided with an article-receiving bore for guiding the article to the collet.

3. In structure for guiding articles through a coating substance, a guide body adapted for at least partial immersion in said substance and provided with a passage for the substance thereto; a collet reciprocably mounted within the body and provided with an article-receiving bore therethrough having an outlet end adjacent said passage, said collet including a number of interconnected, resilient segments; and means in the body engaging the collet for compressing the segments to vary the diameter of said bore upon reciprocable movement of the collet in the body.

4. In structure for guiding articles through a coating substance, a guide body adapted for at least partial immersion in said substance and provided with a passage for the substance thereto; a collet reciprocably mounted within the body and provided with an article-receiving bore therethrough having an outlet end adjacent said

passage, said collet including a number of interconnected, resilient segments; means in the body engaging the collet for compressing the segments to vary the diameter of said bore upon reciprocable movement of the collet in the body; and a doctor plate carried by the body and spaced from said outlet end for removing excess substance from the article.

5. In structure for guiding articles through a coating substance, a guide body adapted for at least partial immersion in said substance and provided with a passage for the substance thereto; a collet reciprocably mounted within the body and provided with an article-receiving bore therethrough having an outlet end adjacent said passage, said collet including a number of interconnected, resilient segments; means in the body engaging the collet for compressing the segments to vary the diameter of said bore upon reciprocable movement of the collet in the body; a doctor plate carried by the body and spaced from said outlet end for removing excess substance from the article; and a liner within the body for guiding the article to the collet, said collet being disposed between the liner and the doctor plate.

6. In structure for guiding articles through a coating substance, a guide body adapted for at least partial immersion in said substance and provided with a passage for the substance thereto; a collet reciprocably mounted within the body and provided with an article-receiving bore therethrough having an outlet end adjacent said passage, said collet including a number of interconnected, resilient segments; and a cam ring secured to the body around the collet, said collet being provided with a cam surface engaging the ring, whereby the diameter of the bore is varied as the collet is reciprocated in the body.

7. In structure for guiding articles through a coating substance, a guide body adapted for at least partial immersion in said substance and provided with a passage for the substance thereto; a collet reciprocably mounted within the body and provided with an article-receiving bore therethrough having an outlet end adjacent said passage, said collet including a number of interconnected, resilient segments; a cam ring secured to the body around the collet, said collet being provided with a cam surface engaging the ring, whereby the diameter of the bore is varied as the collet is reciprocated in the body; and spring means interposed between the body and the collet for yieldably urging the latter in one direction.

8. In structure for guiding articles through a coating substance, a guide body adapted for at least partial immersion in said substance and provided with a passage for the substance thereto; a collet reciprocably mounted within the body and provided with an article-receiving bore therethrough having an outlet end adjacent said passage, said collet including a number of interconnected,

resilient segments; a cam ring secured to the body around the collet, said collet being provided with a cam surface engaging the ring, whereby the diameter of the bore is varied as the collet is reciprocated in the body; a pressure ring within the body engaging the collet; and spring means interposed between the body and the collet for yieldably urging the latter in one direction; a pressure ring within the body engaging the collet.

9. In structure for guiding articles through a coating substance, a guide body adapted for at least partial immersion in said substance and provided with a passage for the substance thereto; a collet reciprocably mounted within the body and provided with an article-receiving bore therethrough having an outlet end adjacent said passage, said collet including a number of interconnected, resilient segments; a cam ring secured to the body around the collet, said collet being provided with a cam surface engaging the ring, whereby the diameter of the bore is varied as the collet is reciprocated in the body; spring means interposed between the body and the collet for yieldably urging the latter in one direction; a pressure ring within the body engaging the collet; and means interlocking the collet and the pressure ring for release from the latter and removal from the body upon compression of said spring means against the cam ring.

10. In structure for guiding articles through a coating substance, a guide body adapted for at least partial immersion in said substance and provided with a passage for the substance thereto; a collet reciprocably mounted within the body and provided with an article-receiving bore therethrough having an outlet end adjacent said passage, said collet including a number of interconnected, resilient segments; a cam ring secured to the body around the collet, said collet being provided with a cam surface engaging the ring, whereby the diameter of the bore is varied as the collet is reciprocated in the body; spring means interposed between the body and the collet for yieldably urging the latter in one direction; a pressure ring within the body engaging the collet; means interlocking the collet and the pressure ring for release from the latter and removal from the body upon compression of said spring means against the cam ring; and a liner for guiding the article to the collet, said liner being reciprocable in the body to and from a position engaging the pressure ring to shift the latter out of engagement with the collet in a direction compressing said spring means.
